UNITED STATES PATENT OFFICE.

WILLIAM G. HUMPHREY, OF TORONTO, ONTARIO, CANADA.

TRAY-SLIDE ATTACHMENT FOR PRINTING-PRESSES.

1,073,131.

Specification of Letters Patent. Patented Sept. 16, 1913.

Application filed January 11, 1913. Serial No. 741,441.

To all whom it may concern:

Be it known that I, WILLIAM G. HUMPHREY, a subject of the King of Great Britain, and a resident of the city of Toronto, in the Province of Ontario, Dominion of Canada, have invented certain new and useful Improvements in Tray-Slide Attachments for Printing-Presses, of which the following is a specification.

10 The invention relates to improvements in fly boards for printing presses as described in the present specification and illustrated in the accompanying drawings that form part of the same.

15 The invention consists essentially of the novel arrangement and construction of parts whereby a fly board has a pair of laterally adjustable side boards arranged thereon and longitudinally flanged on the inner sides thereof to receive the plurality of interchangeable tray slides.

The object of the invention is to provide a fly board having a tray slide which will accommodate a plurality of trays and facilitate the removal of the printed matter with a minimum loss of time.

Referring to the drawings, Figure 1 is a perspective view of the delivery end of a printing press showing the invention secured in position. Fig. 2 is a cross-sectional view of the invention showing the trays arranged thereon.

Like numerals of reference indicate corresponding parts in each figure.

35 In the drawings, 1 is the delivery end of a printing press.

2 is part of the grass-hopper-fly common to some types of printing presses and 3 are the tumblers customarily used with the 40 grass-hopper-fly.

4 is a fly-board or receiving plate secured to the printing press and unto which the printed matter is deposited in an automatic manner by the grass-hopper-fly.

45 5 are pairs of laterally extending series of orifices adjacent each side of the fly-board 4.

6 is a pair of parallelly arranged boards secured in upright manner along the top of 50 the fly-board toward each side thereof by means of suitable brackets 7, the said brackets being in alinement with the laterally arranged orifices 5 in the fly-board so that the bolts or screws by which the brackets are

secured to the said fly-board may fit through 55 the said orifices 5 in order that the side bars may be adjusted laterally in order to accommodate different sized trays according to the size of the printed matter desired.

8 are a pair of angle irons secured longitudinally to the inner face of the side bars 6 by means of bolts or screws.

9 are a pair of trays of any desired construction, one of said trays being supported by the projecting ledges of the angle irons 65 8 and slidably arranged thereon, the other tray being slidably arranged on the fly-board under the projecting ledges of the said angle irons.

The manner of operation is as follows: 70 The trays 9 are arranged in position before the printing press is started. The printed matter during the operation of the press is delivered by the grass-hopper-fly or whatever means is used on the printing press 75 for delivering the printed matter to the top tray, the said trays being in vertical alinement. When this tray has been filled to capacity, it is removed from the tray-slide by a truck or by any convenient means, 80 thereby obviating the necessity of stopping the press as is customary at the present time, the printed matter thereafter being delivered to the bottom tray. When the bottom tray has been filled to capacity the 85 top tray is again slid into position in order to receive the printed matter and the bottom tray is removed to be emptied. There is no loss of time and the jarring of the printed matter by the stopping of the press 90 hitherto experienced in removing the printed matter is obviated, and consequently there is no danger of smearing any of the printed sheets.

The invention is simple and durable in 95 construction and is an inexpensive article to manufacture. It can be readily adjusted and secured to the delivery end of any type of printing press and will not only prove a saving of time but will also insure clear and 100 clean printed matter.

What I claim as my invention is:

In a fly-board for printing presses or the like having orifices therethrough arranged in pairs of laterally extending series adjacent each side thereof, a pair of side boards, angle irons longitudinally secured to the inner face of said side boards, brackets se

cured to said side boards and adjustably secured in said orifices and a plurality of interchangeable tray slides resting upon said fly board and said angle irons between 5 said side boards.

Signed at city of Toronto in the county of York, in the Province of Ontario, in the

Dominion of Canada, this 4th day of May 1912.

WILLIAM G. HUMPHREY.
